UNITED STATES PATENT OFFICE

1,937,926

HOSE SUPPORTER FASTENER

Russell E. Tupper, Beverly, Mass.

Application December 2, 1932. Serial No. 645,445

5 Claims. (Cl. 24—245)

This invention relates to hose supporters and more particularly to that part thereof designated as the loop adaptable to engage a rubber button used in connection therewith and in combination with which means are provided for attaching the top of stockings such as are commonly worn by women.

It has for its purposes to provide a new and novel loop construction designed to function efficiently in use, formed from a single piece of wire and secured in finished position by a unit stamped preferably from metal; to materially reduce the cost of construction; to minimize manufacturing operations; to provide a loop, the upper part of which is smooth and unbroken so that the webbing strap may be readily attached without the use of ferrules or other additional parts; to provide new and novel means to secure and hold the loop in proper shape and to avoid spreading; to provide a combination web attaching link and button loop, in one piece to avoid friction and wear; to so form the wire portion of the combination loop and web attaching link that when the stamping unit is applied thereto, its holding force grips the lower portion of the web attaching link, and also the wire portions extending therefrom in the direction of the button loop, and thereby substantially reinforce and strengthen the loop and link construction; by triangular projection of the wire portions of the device, extending from the web attaching link to the button loop to materially increase the strength of construction, to eliminate wear otherwise inevitably experienced; and to provide the various other advantages and results made evident from the following specification.

I accomplish the objects of my invention by forming a web attaching link and a button loop from a single piece of wire doubled on itself at the bottom to form a button engaging loop, extended upwardly on each side, widened to provide a space for receiving the button, and having a bridge across the top of said space formed from said single wire, said wire flaring inwardly below said bridge to form two opposite, nearly parallel arms to function as the connection between said button loop and web attaching link, said wires again bent outwardly, upwardly, and inwardly above said bridge to form a web attaching link, both ends of said wire terminating at the said bridge, and a stamping unit encircling said ends and also those portions of said wire which connect said loop and link to cover the same and hold the ends securely in place.

Referring to the accompanying drawing which forms a part of this specification, and in which similar letters of reference refer to similar parts throughout the various views, Figure 1 shows one portion of my device made in the single wire construction. Figure 2 shows the stamped unit designed for use on the wire portion shown in Figure 1. Figure 3 shows the assembled device with the stamped portion, shown in Figure 2, in position on the single wire portion, shown in Figure 1. Figure 4 is a cross sectional view on the line X—X in Figure 3, and shows the manner in which the stamping unit clamps the wire ends in fixed position to form the bridge between the web attaching link and button loop. Figure 5 is a cross section on line Y—Y in Figure 3.

Referring again to the drawing, A shows the web attaching link. B shows the button loop. C and C² show the wire ends which form the bridge. C³ shows a portion of the wire which the stamping D grips. D shows the stamping unit hereinbefore described, the edge D² of which clamps over the wire ends C and C² as shown in Figure 4, and the edge D³ of which clamps the wire at C³.

While I have illustrated and described a preferred construction for carrying my invention into effect, this is capable of variation or modification without departing from the spirit of the invention. I therefore do not wish to be limited to the exact details of construction herein set forth, but desire to avail myself of such variations and modifications as come within the scope of the appended claims.

Having thus described my invention I claim as new and desire to secure by Letters Patent of the United States of America:—

1. As an article of manufacture, a combination button loop and web attaching link formed from a single piece of wire doubled on itself at the bottom to form a button engaging loop, extended upwardly on each side, widened to provide a space for receiving the button, and having a bridge across the top of said space formed from said single wire, said wire flaring inwardly below said bridge to form two opposite, nearly parallel arms to function as the connection between said button loop and web attaching link, said wires again bent outwardly, upwardly, and inwardly above said bridge to form a web attaching link, both ends of said wire terminating at the said bridge, and a stamping unit encircling said ends and also those portions of said wire which connect said loop and link to cover the same and hold the ends securely in place.

- cover the same and hold the ends securely in place.
2. As an article of manufacture a combination of a holding unit of stamped material with a single piece of wire, the opposite ends of which terminate at a single point to form a bridge between a button loop formed by said wire and a web attaching link above said loop also formed from said wire, said wire being doubled upon itself to form said button engaging loop and extending upwardly on each side, widened to provide space for receiving the button and extending from said button engaging loop outwardly but nearly parallel and upwardly to said web attaching link, said holding unit encircling said ends and those portions of said wire which connect said loop and link to cover the same and hold the ends securely in place.
3. As an article of manufacture a combination button loop and web attaching link formed from a single piece of wire bent upon itself to form the button loop and web engaging link, the ends of which wire terminate at a single point and forming a bridge intermediate said loop and link and a stamping unit encircling
- said ends and also those portions of said wire which connect said loop and link to cover the same and hold the ends securely in place.
4. In a device of the character described a combination button loop and a web engaging link, formed from a single piece of wire bent upon itself to form the button loop and web engaging link, the ends of said wire terminating at a single point and forming a bridge intermediate said loop and link, and a stamping unit secured about said ends and about the portions of said wire connecting said loop and link.
5. In a device of the kind described, a combination of a stamping unit with a combined button loop and web attaching link formed from a single piece of wire bent upon itself to form the button loop and web engaging link, the ends of which wire terminate at a single point and providing a bridge intermediate said loop and link, said wire portions connecting said loop and link being nearly parallel and said stamping unit encircling said ends and wire portions so as to securely hold said ends in place.
